UNITED STATES PATENT OFFICE

2,501,921

INSULATOR MOUNTING FOR CURRENT CARRYING WIRES

Anthony B. Supjuct, Kalamazoo, Mich.

Application January 31, 1947, Serial No. 725,454

3 Claims. (Cl. 174—165)

1

This invention relates to insulator mountings for current carrying wires.

The main objects of this invention are:

First, to provide an insulator mounting for current carrying wires such for example as electrically charged fence wires which is effective for the purpose and very simple and economical in structure and easily mounted on a post or support.

Second, to provide a structure of this character in which the insulator spools may be quickly and easily secured to a supporting spindle and removed therefrom repeatedly without injury to the parts.

Objects relating to details and economies of the invention will appear from the description to follow. The invention is defined and pointed out in the claims.

A preferred embodiment of the invention is illustrated in the accompanying drawing, in which:

Fig. 1 is a fragmentary view partially in vertical section of an insulator mounting embodying the invention mounted on an iron post or support, the initial position of the bendable spool retaining elements being shown by dotted lines.

Fig. 2 is a fragmentary view in horizontal section of a modified form or embodiment of the invention in which the shank is adapted for mounting on a round post or rod.

Fig. 3 is a fragmentary view with the insulator spool omitted, showing the supporting spindle welded to a supporting post.

In the accompanying drawing, 1 represents an angled fence post or support, and 2 a round post or support. The round post or support illustrated is shown as solid but commonly such posts are tubular.

The insulator spool 3 is formed of glass or porcelain or other suitable insulating material and is provided with a longitudinal bore 4 countersunk at 5 at its outer end. The exterior of the insulator spool is provided with annular peripheral grooves 6 adapted to receive attaching wires 7 for the current conducting wires 8, a barbed wire being illustrated in the drawing although plain wires are quite commonly used for electrically charged fence strands.

The spool supporting spindle 9 is provided with a shank 10 disposed angularly thereto. The spindle and shank are formed of an integral rod-like member bent to dispose the shank at an angle to the spindle. The inner end of the insulator spool is countersunk at 51 to permit engagement of the spool with the shank 10 in spaced relation from the bend between the spindle and

2

shank. In the embodiment of Fig. 1 the shank is provided with a tapered tip 11 facilitating the driving of the shank into a wooden post and it is also threaded at 12 to receive nuts 13 for clamping the shank in a hole 14 of the post 1. The end of the spindle has a longitudinal kerf 15 therein providing bendable fasteners 16 which may be spread outwardly into the countersink 5 as shown by full lines in Fig. 1 for retaining the insulator spool on the spindle with the spool resting upon or supported by the shank of the spindle. The bendable fastener elements permit the removal of the spool 3 as occasion may require.

Electrically charged fence wires are frequently used to provide temporary enclosures although the electrically charged wires are sometimes used in strands of a wire fence. Where used to provide temporary enclosures it is particularly desirable to provide the insulator mountings which permit the removal of the insulators.

In the embodiment shown in Fig. 2, the shank 17 corresponding to the shank 10 of Fig. 1 is provided with an eye 18 adapted to be sleeved over the support 2 and clamped in position thereon by means of the set screw 19. In the embodiment shown in Fig. 3, the shank 20 is not pointed or provided with threads as in Fig. 1 but is designed to be welded as indicated at 21 to the post. It will be appreciated of course that the shank 10 could be welded instead of being driven into a post or secured by nuts. However, it is more economical to provide structures such as shown in Fig. 3 where it is intended to secure the shank by welding to the post. The shanks may be welded to any type of fence post and these are quite commonly of angle section.

While I have particularly stressed the use of the insulator mounting on electrically charged fence wires there are many other uses, the structure being particularly desirable where temporary current carrying wires are to be mounted—for example in various kinds of field operations, road construction, and the like.

I have illustrated practical embodiments of the invention which it is believed will enable those skilled in the art to adapt the invention as may be desired for the particular conditions.

Having thus described my invention, what I claim as new and desire to secure by Letters Patent, is:

1. An insulator mounting adapted for current carrying wires comprising an insulator spool to which the wire may be attached, the spool having a longitudinal bore countersunk at its outer end, and a supporting spindle of generally circular

cross section adapted to receive said insulator spool and having its outer end slit longitudinally and diametrically to provide bendable fastener elements spreadable into said countersink of said insulator spool bore, the spindle having an integral laterally disposed supporting shank with which the inner end of the insulator spool is in supporting engagement when the spool is secured upon the spindle by said bendable elements thereof, the shank having a pointed end and also being threaded whereby it may be driven into a wooden post or support or secured to an iron post or support by means of nuts.

2. An insulator mounting adapted for current carrying wires comprising an insulator spool to which the wire may be attached, the spool having a longitudinal bore countersunk at its outer end, and a supporting spindle adapted to receive said insulator spool and having its outer end slit longitudinally to provide bendable fastener elements spreadable into said countersink of said insulator spool bore, the spindle having an integral laterally disposed supporting shank with which the inner end of the insulator spool is in supporting engagement when the spool is secured upon the spindle by said bendable elements thereof, said fastener elements being disposed in opposed relation to each other and being bendable towards and from each other in a common plane, said countersink being of substantial dimensions and said fastener elements being bendable a substantial distance from each other within said countersink.

3. An insulator mounting for wires adapted to be electrically charged, comprising an insulator having a longitudinal bore countersunk at its outer end, and a supporting spindle having an

integral shank disposed substantially at right angles thereto and adapted for attachment to a post, the spindle having a longitudinal kerf at its outer end providing bendable fastener elements, the spindle being of such length that the insulator is supported by the shank when the insulator is arranged on the spindle and its fastener elements bent outwardly into the countersink thereof in retaining engagement therewith, said fastener elements being disposed in opposed relation to each other and being bendable towards and from each other in a common plane, said countersink being of substantial dimensions and said fastener elements being bendable a substantial distance from each other within said countersink.
